CLAIM

The ornamental design for a hand-held radar device, as shown and described.

DESCRIPTION

This patent application is being concurrently filed with commonly owned utility U.S. patent application Ser. No. 12/590,145, entitled “Noise-cancelling Down-Converting Detector”, by Grant E. Moulton, Steven H. Goody, and Christopher E. Stewart; and with commonly owned utility U.S. patent application Ser. No. 12/590,117, entitled “Method of Down Converting High-frequency Signals”, by Christopher E. Stewart, Grant E. Moulton, and Steven H. Goody; and with commonly owned utility U.S. patent application Ser. No. 12/590,116, entitled “Continuous-Wave Field Disturbance Sensing System”, by Christopher E. Stewart, Grant E. Moulton, and Steven H. Goody.

FIG. 1 is an isometric view of a hand-held radar device showing our new design.

FIG. 2 is a front plan view thereof.

FIG. 3 is a rear plan view thereof.

FIG. 4 is a bottom end view thereof.

FIG. 5 is a top end view thereof.

FIG. 6 is a right side view thereof; and,

FIG. 7 is a left side view thereof.

Any broken line illustration of structure in the drawing is not part of the design sought to be patented.
